UNITED STATES PATENT OFFICE.

JOHN H. THOMAS, OF SPRINGFIELD, OHIO.

HAY-TEDDER.

SPECIFICATION forming part of Letters Patent No. 309,745, dated December 23, 1884.

Application filed May 29, 1884. (No model.)

To all whom it may concern:

Be it known that I, JOHN H. THOMAS, of Springfield, county of Clark, and State of Ohio, have invented a new and useful Improvement 5 in Hay-Tedders, of which the following is a full, clear, and exact description, reference being had to the accompanying drawings, making part of this specification.

This invention relates to the means for throwing the pinions of the crank-shaft actuating the tedder forks or teeth into and out of gear; and it consists in mounting the main axle of the machine in tubular bearings on the frame through eccentrics on the axle, and in providing 15 one or more of these eccentrics with a toothed segment, which engages with and is adapted to be rocked by means of a toothed segment, and lever for actuating the same, pivoted to the frame, whereby by the rocking of 20 the eccentrics in their bearings the frame is moved forward or backward relative to the driving-wheels for throwing the pinions into and out of gear.

It further consists in connecting the lever 25 adjustably with the toothed segment for rocking the eccentric in its bearings and adjusting the frame and pinion-shaft, as hereinafter explained.

The machine in its organization or general 30 arrangement of parts is similar to others in use, and it need not, therefore, be described in detail further than is necessary to an understanding of my improvements.

In the accompanying drawings, Figure 1 is 35 a plan view of a tedder embracing my improvements. Fig. 2 is a cross-section on a line adjacent to the adjusting-lever and toothed segments. Fig. 3 represents the toothed segments and a portion of the actuating-lever in side 40 elevation enlarged, with the slotted plate for effecting the adjustment of the lever relatively to its segment partly broken away to show the ribbed or corrugated adjacent face of the segment. Fig. 4 is a side elevation looking from 45 the opposite side; and Fig. 5 is a transverse vertical section of said parts, showing the axle in elevation.

A represents the main axle of the machine, and B B the carrying-wheels mounted and revolving freely thereon, and provided each with

an internally-cogged ring, B², secured to its inner side and revolving with it.

The main frame may be constructed in any usual or preferred manner. As shown, it consists of a main transverse bar, C, and a series 55 of longitudinal bars, C' C² C³, rigidly connected at their forward ends to the bar C, and extending thence rearwardly over the axle, forming supports for the bearings of the crank-shaft a, through which motion is imparted to the tedder forks or teeth, and also points of attachment of the links or radius-bars supporting the upper ends of the fork-stakes. The shaft a has pinions a' fast on its ends, adapted to engage with the internally-toothed rims B² for 60 actuating it. The side longitudinal bars, C' C², and by preference, also, one of the intermediate bars, (indicated by C³), have pendent brackets D secured to them, provided with tubular bearings or short transverse sleeves 65 D', in which are mounted collars E, surrounding the axle A, and of eccentric formation relative thereto, as shown in Fig. 4. These eccentrics or collars snugly fill the sleeves D', and are adapted to be rocked therein. They 70 are secured to the axle in any suitable manner, and preferably those at the sides are provided on their outer ends with annular flanges similar to that shown at e, Fig. 5, which abut against the outer ends of the bearing-sleeves 75 and prevent relative lateral movement of the frame and axle. One of these eccentrics, preferably the intermediate one where more than two are used, as being in convenient position to be acted upon by the attendant, and as being 80 less liable to produce torsional strain of the axle, has its flange e provided with a toothed portion, e', which is engaged by and is adapted to be acted upon by a similar toothed segment, f, formed on a pendent sector plate or quadrant, F, pivoted at g in a bracket, G, on the bar C². The pivot g extends through and beyond the hub f' of the quadrant F, and has pivoted upon it a pendent plate, h, having flanges h' on its outer face, forming a socket, 85 in which the hand-lever H is secured by one or more bolts or screws, as shown. The lower end of plate h is expanded in width, and has a slot, h², formed in it in an arc of a circle of which the pivot g is the center, and a bolt, i, 90

passing through a perforation in the quadrant F; and the slot h^2 in plate h, in connection with a clamping-nut, i', serves to hold the plate h and the lever H secured thereto at any desired adjustment relative to the sector F permitted by the slot h^2 . The quadrant F and plate h have intermeshing radial ribs formed on their adjacent faces at f^2 in an arc of a circle outside of the slot h^2 , which assist in holding the said parts at the desired adjustment, the object of such adjustment being to bring the lever into convenient position to be operated by the attendant. The bracket G has an upright notched segment, G', formed upon it, with which a sliding latch, k, on the lever H engages for holding the lever, and with it the axle-eccentrics, at any desired adjustment, said latch being operated by a spring and a bell-crank or thumb lever on the hand-lever of any usual or preferred form and arrangement.

Under the arrangement of parts shown and described it will be seen that when the axle-eccentrics are rocked in their tubular bearings the frame of the machine, carrying the pinion-shaft, will be moved forward for throwing the pinions a' out of gear with the internally-toothed rings B^2 , or backward for throwing them into gear, as desired.

30 The segment f is preferably made in an arc of a circle of larger diameter than segment e' , as shown, for diminishing the throw of lever H required for effecting the adjustment described.

35 Having now described my invention, I claim as new—

1. In a hay-tedder, an eccentric on the axle, in combination with the toothed segments for rocking said eccentric and throwing the pinion-shaft into or out of gear, substantially as described.

40 2. The frame-bars provided with sleeve-bearings, in combination with the eccentrics

on the axle journaled in said sleeve-bearings, for adjusting the frame and pinion-shaft, and 45 provided with annular flanges for preventing relative lateral movement of the frame and axle, substantially as described.

3. The combination, in a hay-tedder, of the tubular bearing-sleeves on the frame, the eccentrics on the axle adjustable in said sleeves, and the intermeshing toothed segments and lever for rocking the eccentrics in the bearing-sleeves and adjusting the frame for throwing the forks into or out of action, substantially 55 as described.

4. The eccentric on the axle, provided with the toothed segment, and mounted in a suitable bearing on the frame, in combination with the toothed segment adjustably secured to the hand-lever, for adjusting the frame and throwing the fork-actuating pinions into and out of gear, substantially as described.

5. The toothed sector or quadrant for rocking the axle-eccentric and adjusting the frame, 65 in combination with the lever socket or plate to which the adjusting-lever is secured, said lever socket or plate being adjustably connected with said toothed sector, substantially as described.

70 6. In a hay-tedder, the axle-eccentric provided with the toothed segment, in combination with a toothed lever-segment of greater radius or formed in an arc of a circle of greater diameter than the segment on the eccentric, 75 whereby the throw of the lever in adjusting the frame for throwing the machine into or out of gear is diminished, substantially as described.

In testimony whereof I have hereunto set my hand this 28th day of May, A. D. 1884.

J. H. THOMAS.
